UNITED STATES PATENT OFFICE.

ADOLPH C. HANSEN, OF CHICAGO, ILLINOIS, ASSIGNOR OF ONE-HALF TO
GEORGE J. ORDNUNG, OF SAME PLACE.

DESIGN FOR A MATCH-LIGHTER.

SPECIFICATION forming part of Design No. 33,460, dated October 30, 1900.

Application filed August 31, 1900. Serial No. 28,718. Term of patent 7 years.

To all whom it may concern:

Be it known that I, ADOLPH C. HANSEN, a citizen of the United States, residing in the city of Chicago, in the county of Cook and State of Illinois, have invented and produced a new and original Design for a Match-Lighter, of which the following is a specification, reference being had to the accompanying drawings, forming part hereof.

In the drawings, Figure 1 is a side elevation of a device embodying my invention. Fig. 2 is a side elevation thereof in a plane at right angles to that of Fig. 1. Fig. 3 is a bottom plan view thereof.

The leading or characteristic features of a match-lighter embodying my novel design embrace a flat base-plate which constitutes one end of the device and two arms or jaws extending from one side of said base-plate in generally perpendicular relation to the base-plate and parallel relation with each other and symmetrically disposed with respect to each other and to said base-plate. Said arms are of decreasing width from their inner to their outer ends and are joined at their in-

ner ends to the opposite edges of the plate. Said inner or widened ends of the arms are for a distance inwardly from the edges of the plate deflected abruptly inward, while the outer or principal parts of the arms are adjacent to and nearly parallel with each other. The arms are provided near their outer ends with integral spurs the free ends of which are bent inwardly and project inside the inner surfaces of the arms. Two of such spurs are formed on each arm, and the pair of spurs on one arm are located in advance of the pair on the other arm. The base-plate is provided centrally thereof with an opening extending therethrough. 30 35 40

I claim as my invention—

The design for a match-lighter, substantially as herein shown and described.

Signed at Chicago, Illinois, this 25th day of August, A. D. 1900.

ADOLPH C. HANSEN.

In presence of—

C. CLARENCE POOLE,
GERTRUDE BRYCE.
